UNITED STATES PATENT OFFICE.

GLENN H. CURTISS, OF HAMMONDSPORT, NEW YORK, ASSIGNOR TO THE CURTISS MOTOR CO., OF HAMMONDSPORT, NEW YORK, A CORPORATION OF NEW YORK.

FLYING-BOAT.

1,246,011.

Specification of Letters Patent. Patented Nov. 6, 1917.

Application filed December 11, 1914. Serial No. 876,714.

To all whom it may concern:

Be it known that I, GLENN H. CURTISS,
a citizen of the United States, residing at
Hammondsport, in the county of Steuben,
5 and State of New York, have invented cer-
tain new and useful Improvements in Fly-
ing-Boats, of which the following is a speci-
fication.

be removed from the boat without disturbing the connection of the bottom section thereto. Not only is the post prevented from becoming an obstruction in packing for shipment, but the deck may be made water tight at the point where the post passes through it. The joint 21 shown in detail in Fig. 4 comprises a pair of side straps 22

My invention relates to flying boats generally and has for its object to improve the construction thereof in points of assembling and knocking down, and combining maximum strength with maximum simplicity. In the accompanying drawings I illustrate my invention as applied to a flying boat of the so called Curtiss type, but it will be readily understood that my invention may be applied in this form or in some generally related form to other types of aircraft as well. The tail of the boat as shown in Figs. 1-75

Of the drawings Figure 1 is a side elevation of the flying boat, and 5 is provided in its top with a downwardly and forwardly extending water-shed.

Fig. 2 is a top plan view thereof, and the tight socket 26. This socket receives the

45 tween this upwardly inclined prow 19 and the motor 17 there is arranged a post brace 20 to take the shock of impact and prevent collapse of the elevated aerial and motor structures upon the prow due to any combined forces of impact and motor inertia. This post I divide into upper and lower sections by a breakable joint 21 at a point near the prow 19 and just above the top 50 for shipment the top section of post 20 may Engine frame 31 (see Fig. 3) is constructed of steel tubing and comprises front and rear sections (see Fig. 2) which support at their upper ends the beams 32 of the engine bed. Each section of the engine frame comprises a pair of spaced legs 33 spaced apart by diagonal braces 34. The feet 35 of the frame are bolted directly to both the structure of the supporting surfaces 15 and the body of the boat 10, the supporting surface 15 immediately adjacent 55 to

the side of the boat being constructed as a part of the boat as clearly set forth in my application Serial Number 790,050 filed September 16th, 1913. The frames 31 thus straddle the central section and bind the two sides of the boat structure together. A strap 36 interconnects the feet 35 and prevents spreading thereof under such strain as might disrupt the boat structure about the longitudinal axis thereof. This strap conforms closely to the deck of the boat which as has been stated has a longitudinal section approximately that of surface 15. In the middle the strap is slightly bowed both to permit slight adjustment and to accommodate the upper surface of the tail 37 which emanates from this point. At one or both ends it may be provided with an adjusting bolt 38 which passes through the foot of the frame 31. At the frame's upper end a long bolt 39 inter-connects the leg ends, and by adjusting nut 40 on one end of this bolt the upper ends of legs 33 may be adjusted toward or from each other to exactly position the spaced beams 32 of the engine bed. This bolt may be used also to spread the feet 35 in fitting the frame to the boat 10, the nut 40 being loosened or tightened as may be needed. After the frame is secured to the boat, nut 40 may be readjusted to properly space the upper ends of legs 33.

Connected directly with the upper ends of legs 33 by linking bolts 41 are forked extensions 42 the apexes of which project above the upper supporting surface 15 and are each provided with an eye 43 arranged to receive the hooks of cable or hoisting connections. These eyes are located it will be observed one at each end of the engine frame and therefore one on each side of the center of gravity of the craft and also in the vertical plane of the longitudinal axis thereof. By this means the craft may be hoisted from the surface of the water or placed thereon without straining any of the less strong parts. Eyes 43 are connected directly and metallically through the engine frame with the body of the boat 10 as well as with the engine bed 32, and they thereby bear directly all of the heaviest structures of the craft and the weight of such structures is moreover symmetrically distributed. The usual course in using these eyes is to connect harness in the fashion shown in Fig. 1.

The ailerons 16 are provided with two legged or forked operating braces 44 the feet 45 of which are secured to the aileron structure. The apex of the fork is formed by flattening and rounding, or welding together the upper ends of the legs. A crown plate 46 of thin sheet steel is fitted over the apex. The crown plate is provided with a series of perimetral perforations 47

arranged to receive cable connections 48 some of which are brace wires which extend to various points on the surface of the aileron, and one at least of which is an operating cable 49.

70

What I claim is:

1. A flying boat comprising a hull, an element mounted above the hull, brace sections between the element and the hull, means respectively fixedly and removably mounting opposite ends of the brace sections to the hull and to the element and means joining adjacent ends of the sections.

2. A flying boat comprising a hull, supporting surfaces mounted across the hull and brace means between the surfaces and the hull, including an interior brace section fixed within the hull, a continuing exterior section removably connecting to the surfaces and means separably associating the sections.

3. A flying boat comprising a boat structure, aerial supporting surfaces mounted transversely of said structure, an elevated driving motor, a stool structure fixed within the boat, a brace section seated upon said stool structure, an aligned brace section detachably connected to said motor and means removably connecting the brace sections.

4. A flying boat comprising a boat structure, having an impact-distributing landing prow, a stool erected within the prow of said boat, a brace section fixedly mounted by said stool, aerial supporting surfaces for the boat structure, a second brace section connected to said surfaces with the first said brace section and a break joint normally connecting said brace sections to support said surfaces from the landing prow through said stool, said joints forming means whereby the said second brace section may be detached from the boat structure without interfering with the connection of the first said section therewith.

5. A flying boat comprising a boat structure, aerial supporting surfaces mounted transversely of said structure aft of the prow thereof, an elevated driving motor, a post brace arranged between said driving motor and said prow to take the thrust of impact thereupon and having its base end seated upon a stool structure having legs radiating to various portions of the bottom.

6. A flying boat comprising a boat structure, aerial supporting surfaces arranged transversely thereof, elevating and steering controls and a vertical stabilizing fin mounted upon the tail of the boat, a water-tight socket in said tail, and a beam incorporated in the structure of said stabilizing fin and having its base end seated in said socket.

7. A flying boat comprising a boat structure, aerial supporting surfaces arranged transversely thereof, a stabilizing fin, a socket in the tail of said boat, and a beam incorporated in said fin structure and having its base end seated in said socket.

130

8. The combination with an aeroplane body of a stabilizing fin therefor, and a beam arranged in the structure of said fin for projection into said aeroplane body.
- 5 9. The combination with an aeroplane of a stabilizing fin for the aeroplane, said fin being of approximately right triangular shape and including a diagonal bracing beam extending from the apex of one acute
- 10 angle to and beyond a medial point on the opposite side into said aeroplane.
10. A flying boat comprising a boat structure, aerial supporting surfaces arranged transversely of said structure, separate frames secured to said boat structure respectively fore and aft of the center of gravity and continuing frames projecting upwardly from the first said frames and through one of said surfaces to provide hoisting connections for the boat.
- 15 11. An aeroplane comprising aerial supporting surfaces, engine frames arranged between the surfaces, an engine bed supported by said frames between said surfaces and continuing frames for the first said frames projecting from said bed through one of said surfaces to provide direct hoisting connections for said surfaces and said engine bed together.
- 20 12. A flying boat, comprising a boat structure, an aerial supporting surface arranged above said boat structure, frames mounted directly upon said boat structure, an engine bed engaged and supported by said frames, and a continuing frame for each of the first said frames adapted to engage both the latter and said engine bed and to project through said supporting surface to provide hoisting connections for the boat.
- 25 13. In an aeroplane, an engine, supporting surfaces, frames supporting the engine between the surfaces, eyes for making hoisting connections and located in the vertical plane of the longitudinal axis of the aeroplane at each end of said engine and frames continuing the first said frames from the engine for the provision of said eyes.
- 30 14. An aeroplane comprising a chassis structure, aerial supporting surfaces mounted thereon and projecting laterally therefrom on each side thereof, a centrally located engine frame having spreading legs connecting together parts connected with said surfaces and lying on opposite sides of the longitudinal axis, and a strap mem-
- ber interconnecting the feet of the frame whereby abnormal spreading of legs is restrained and disruption of the parts prevented.
15. In a flying boat, an engine frame located in the plane of the longitudinal axis of the craft and having spreading legs the feet of which are respectively secured to portions of the structure on opposite sides of the longitudinal axis, and a strap interconnecting the feet of the frame on opposite sides of said axis whereby the legs are prevented from spreading apart and disrupting the structure upon the application of undue strains.
- 60 16. In an aeroplane, an engine frame comprising legs spaced apart by diagonal braces between them and adjustable interconnecting means adjacent one end thereof to adjust the distance between them.
- 65 17. In an aeroplane, superposed supporting surfaces, engine bed beams mounted between said surfaces, a motor supported by and between said beams to prevent inward displacement thereof, and a support for the engine bed beams comprising upwardly converging legs terminally engaging beneath said beams together with rigid braces crossed beneath the motor to individually brace the respective beams obliquely to the foot of the leg remote therefrom.
- 70 18. The combination of an aeroplane body, of a fin mounted upon the body, brace means for the fin adapted to extend into said body and an elongated socket arranged within the body to wholly support said brace.
- 75 19. A stabilizing surface including a brace centrally embedded within the surface and projecting beyond the limits of the surface and socket means adapted to wholly support said brace exteriorly of the surface.
- 80 20. The combination with an aeroplane body, of a socket arranged therewithin, a brace having its lower portion supported in said socket to project from said aeroplane body and a fin carried by said body and adapted to be centrally intersected by said brace.
- 85 100 In testimony whereof I affix my signature in presence of two witnesses.
